TRAVELING WAVE ELECTRON DISCHARGE
DEVICES

Haig P. Iskenderian, Elmhurst, Ill., assignor to International Telephone and Telegraph Corporation, a corporation of Maryland

Application January 29, 1953, Serial No. 333,861

5 Claims. (Cl. 315—3.5)

This invention relates to electron-optical systems for traveling wave electron discharge devices and more particularly to hollow cylindrical permanent magnet arrangements for such devices.

The traveling wave type of tube is particularly useful in wideband microwave systems since it is capable of amplifying radio frequency energy over an unusually wideband of frequencies. The tube includes a form of transmission line, usually a helix, for transmission of microwave energy for interaction with an electron beam closely associated with the line. The helical characteristic of the transmission line is such that the axial velocity of microwave signals conducted along the helical path is approximately the same as or slightly slower than the velocity of the electrons of the beam whereby the electrical field of the microwave signals interact with the electron beam for amplification of the microwave signals.

In the passage of the electron beam from an electron gun along the length of the transmission line, there is a tendency for the electrons of the beam to deviate from a desired electron beam path and as a result causes an increased electron beam cross-section which eventually will become greater than the diameter of the helical transmission line. This deviation of the beam is caused by the natural space-charge repulsion of electrons along the path of the helix, as well as by some types of electron guns which naturally project a convergent electron beam. In becoming larger than the diameter of the helical transmission line, the electron beam will transfer electron beam current to the helical line which is a feature undesired for maximum amplification, as well as requiring power dissipation on the helical structure. The use of magnetic fields to maintain electron beams uniform in diameter is substantially well understood, which is to say that the required magnetic field for any given application can be predicted. Heretofore, this problem of producing this magnetic field has been solved by employing electromagnets comprising a number of solenoid coils, ranging from one to four separate coils, coaxial of the electron beam path and extending substantially the entire length of the traveling wave propagating structure. These solenoids with their associated current supplying devices are arranged to produce a substantially uniform magnetic field whose lines of flux extend axially of the helical conductor for substantially its entire length to insure a pencil-like beam throughout the entire length of the transmission line.

Thus, traveling wave electron discharge devices have heretofore employed electromagnets to confine the electrons, produced therein by an electron gun, in an axial beam having a small, uniform cross-section throughout the length of the interaction or radio frequency section of a traveling wave device. In a number of traveling

2

wave device applications these electromagnets with the number of coils employed and the circuitry required to establish the regulated current for flow therethrough to produce a desired magnetic field become cumbersome.

5 Further, even with all the current regulating circuitry, the magnetic field produced by these electromagnets often varies enough to produce an undesired effect of beam expansion, thus yielding undesired power operating characteristics. An ordinary permanent magnet of the bar or horseshoe type having associated therewith necessary pole pieces, may be employed to replace the electromagnets as disclosed in the copending application of J. H. Bryant and H. W. Cole, Serial No. 321,342, filed November 19, 1952, entitled "Traveling Wave Electron Discharge Devices" now abandoned. The employment of such permanent magnetic electron-optical systems provides a more economical beam focusing means than the electromagnet type electron-optical systems, however, the magnetic field thus provided is axial over a small portion only of the total length of the interaction section of a traveling wave device, the field having a tendency to decrease in magnetic strength in the central portion thereof. Therefore, it is the object of this invention to provide an electron-optical system of the permanent magnet type for obtaining a substantially uniform axial magnetic field distribution over at least 85% of the length of the interaction section of traveling wave electron discharge devices.

Another object of this invention is the development of 30 a law of magnetization applicable to a hollow cylindrical radially magnetized permanent magnet which yields substantially uniform axial magnetic field distribution over approximately 85% of the length of the cylindrical magnet.

35 A feature of this invention is a method of providing a hollow magnetized cylindrical shell suitable as the electron-optical system for traveling wave type of electron discharge devices. Two identical half cylinders, prior to fabrication into a whole hollow cylinder, are first radially magnetized separately to saturation. The magnetization being such that the inner wall of each half has the same polarity. The halves are then partially demagnetized in predetermined steps along the length to produce the desired axial magnetic field distribution according to the 40 developed law of magnetization for hollow cylindrical permanent magnets.

Another feature of this invention is a method of providing a hollow magnetized cylindrical shell by first magnetizing a plurality of pie-shaped elements with the apex 45 of each of the same polarity and then fabricate them into a hollow cylindrical magnet.

The above-mentioned and other features and objects of this invention will become more apparent by reference to the following description taken in conjunction with the 50 accompanying drawings, in which:

Fig. 1 is a longitudinal sectional view illustrating an application of an embodiment of this invention;

Fig. 2 is a longitudinal sectional view of the electron-optical system of Fig. 1 to aid in the development of the 55 law of magnetization in accordance with the principles of this invention;

Figs. 3 and 4 are graphical representations of certain functions, $M(x)$ and $K''(x-x_0)$, and the magnetic field distribution of a cylindrical shell permanent magnet magnetized radially, respectively, aiding in the development of the law of magnetization;

Fig. 5 is a longitudinal sectional view illustrating the

equipment employed in a method of radially magnetizing a hollow cylindrical shell; and

Fig. 6 is a view in perspective of another embodiment in accordance with the principles of this invention.

Referring to Fig. 1, a traveling wave type electron discharge device 1 is shown to comprise a cylindrical housing 2 of non-magnetic material containing in one end thereof an electron gun unit 3 and in the opposite end thereof a radio frequency interaction section 4. The housing 2 has mounted thereon and concentric thereto an embodiment of an electron-optical system in accordance with the principles of this invention comprising a cylindrical permanent magnet 5 for production of an axial magnetic field to maintain a substantially uniform electron beam throughout the length of section 4.

The housing 2 may be composed of ceramic or non-magnetic metallic material as desired with the internal structure of the electron gun unit 3 following any of the conventional structures presently known in the art. Preferably the device 1 employed with the electron-optical system of this invention should follow the teachings of the copending application of J. H. Bryant and T. J. Marchese, Serial No. 221,862, filed April 19, 1951, now Patent No. 2,788,465. Disclosed therein is the structural arrangement of a traveling wave tube with the terminals for the electrodes of the gun unit at one end of the tube and the terminals for the radio frequency input and output connections at the other end of the tube. The input and output R.-F. connections disclosed therein are of the coaxial type; but may be adapted to function with other forms of waveguide coupling lines if desired.

Referring more particularly to interaction section 4, a radio frequency transmission line 6 preferably in the form of a helix may be supported in a ceramic tubing positioned axially by the magnetic barrier members 8 and 9 and matching transformer sections 10 and 11 located respectively at each end of section 4. It is preferred, however, to support helix 6 in a plurality of dielectric support rods 12 equally spaced about the helix. The transmission line 6 is preferably coated for substantially the first half of its length with lossy material such as aquadag or the like to minimize the reverse R.-F. waves along the conductor 6 and the electric field thereof. If desired the propagating structure may assume other configurations such as a plurality of annular discs or plates, whereby the axial velocity of the radio frequency energy is made preferably slightly slower than the velocity of the beam of electrons projected from unit 3.

The magnet 5 of the electron-optical system of this invention comprising a cylindrical shell 13 must be magnetized according to some prescribed law of magnetization to yield a substantially uniform field herein and for a major portion of the axis of said shell. The following analytical discussion in connection with Figs. 2, 3, and 4 specifies one of the laws of magnetization for shell 13 which yields the desired uniform axial field within the electron-optical system located concentric to the traveling wave tube 1 of Fig. 1.

First consider a cylinder shell 13 which has a distribution of radial magnetization $M(x)$ as illustrated in Fig. 2 where $M(x) = 2l$ times surface pole strength $m(x)$. The potential ΔV at an arbitrary point P or 14 on the axis of cylinder 13 a distance $x_0 - x$ from a circular element dx is given by:

$$(1) \quad \Delta V = 2a^2 \pi \frac{M(x) dx}{[a^2 + (x - x_0)^2]^{3/2}}$$

where a is equal to the average radius of cylinder 13. The corresponding axial component of magnetic field ΔH at point 14 will be:

$$(2) \quad \Delta H = \frac{\partial}{\partial x} (\Delta V) = 6a^2 \pi \frac{M(x)(x - x_0) dx}{[a^2 + (x - x_0)^2]^{5/2}}$$

Equations 1 and 2 may be obtained by utilizing the

formulas and discussion relative thereto as found in the textbook, A. S. Ramsey, "Electricity and Magnetism," second edition, Cambridge at the University Press, Section 8.71, page 201. The total axial magnetic field due to the radially magnetized cylinder 13 is given by:

$$(3) \quad H(x_0) = C \int_{-L}^L \frac{M(x)(x - x_0) dx}{[a^2 + (x - x_0)^2]^{5/2}}$$

where $C = 6\pi a^2$ and L is equal to one half the length of cylinder 13. Denoting

$$(4) \quad \frac{x - x_0}{[a^2 + (x - x_0)^2]^{5/2}} = K(x - x_0)$$

Equation 3 may be written as:

$$(5) \quad H(x_0) = C \int_{-L}^L K(x - x_0) M(x) dx$$

Further utilization of such a permanent magnet as herein disclosed it is desirous to obtain a uniform magnetic field "H" inside and on the axis of the cylinder shell. This implies that,

$$(6) \quad \frac{dH}{dx} \Big|_{x=0} = C \int_{-L}^L K'(x - x_0) M(x) dx = 0$$

for a first approximation, and,

$$(7) \quad \frac{d^2H}{dx^2} \Big|_{x=0} = C \int_{-L}^L K''(x - x_0) M(x) dx = 0$$

for a second approximation, with higher order approximations, if desired, being provided by higher order differentiations of Equation 5 being set equal to zero.

It follows from Equations 6 and 7 that the magnetization function $M(x)$ should be orthogonal to K' and K'' over the limits of integration of $-L$ to L . The determination of $M(x)$ may be obtained by adapting a graphical method of analysis to satisfy Equations 6 and 7.

By setting $Z = x - x_0$ in Equation 4 and differentiating there is obtained:

$$(8) \quad K'(Z) = (a^2 - 4Z^2)(a^2 + Z^2)^{-7/2}$$

and:

$$(9) \quad K''(Z) = 5Z(4Z^2 - 3a^2)(a^2 + Z^2)^{-9/2}$$

It will be seen from Equation 8 that $K'(Z)$ is a symmetrical function, hence Equation 6 will be satisfied for all $M(x)$ which are anti-symmetrical, the simplest one being $M(x) = M_0 x$.

To obtain a higher order of approximations for the desirable form of $M(x)$, representative of a more uniform magnetic field distribution, an attempt should be made to satisfy Equation 7. A plot of $K''(Z)$ is substantially illustrated in Fig. 3 by curve 15.

It will be understood from curve 15 of Fig. 3 that $K''(Z)$ is antisymmetrical; hence, $M(x)$ which must also be anti-symmetrical to satisfy Equation 6, should satisfy Equation 7 over the limits of integration 0 to L , or $-L$ to 0.

In view of the apparent difficulties in the integration of the form

$$\int \frac{x^{n/2}}{[a^2 + (x - x_0)^2]^{5/2}}$$

wherein n is an odd integer, we may try to satisfy Equation 7 by assuming $M(x)$ to be made up of a number of linear functions with varying slopes along the length of cylinder 13. For an approximation we may consider:

$$(10) \quad M(x) = -q + M_1 x \quad \text{for } x = -L \text{ to } -kL$$

$$M(x) = M_1 x \quad \text{for } x = -kL \text{ to } +kL$$

$$M(x) = q + M_2 x \quad \text{for } x = +kL \text{ to } L$$

where k is a parameter less than one and q is a constant equal to the Y-intercept. The curve 16 of Fig. 3 represents the $M(x)$ function as established by Equations 10 wherein the portion 17 has a slope M_1 and portions 18 have a slope M_2 .

The integration of Equation 3, where $M(x)$ is defined by Equations 10, yields:

$$(11) \quad H(x_0) = 2\pi \left\{ \frac{[(M_1 - M_2)(kL - x_0)]}{[b^2 + (kL - x_0)^2]^{1/2}} + \frac{[(M_1 - M_2)(kL + x_0)]}{[a^2 + (kL + x_0)^2]^{1/2}} + \right. \\ \left. \frac{M_2(L - x_0)^2 + [M_2(kL - x_0) - M_1 kL]a^2}{[a^2 + (L - x_0)^2]^{1/2}} + \right. \\ \left. \frac{M_2(L + x_0)^2 + [M_2(kL + x_0) - M_1 kL]a^2}{[a^2 + (L + x_0)^2]^{1/2}} \right\}$$

From Equation 11 $H(x_0)$ is found to be a function of M_1 , M_2 , K , and other physical constants. In order to evaluate $H(x_0)$ it is necessary to determine the values of k and M_1/M_2 . To do so the following boundary conditions may be selected as:

$$(12) \quad H(0) = H\left(\frac{L}{2}\right)$$

and

$$(13) \quad H(0) = H\left(\frac{3L}{4}\right)$$

Manipulation of these two equations will determine the values of k and M_1/M_2 substantially as follows. The values of the magnetic field $H(x_0)$ for $x_0=0$, $L/2$, $3L/4$, and L , may be obtained from Equation 11. For the present case under consideration L/a is chosen to equal approximately nine.

$$(14) \quad H(0) \approx 4\pi \left\{ \frac{(M_1 - M_2)k}{\left[\left(\frac{a}{L} \right)^2 + k^2 \right]^{1/2}} + M_2^2 \right\}$$

$$H\left(\frac{L}{2}\right) \approx \pi \left\{ \frac{(M_1 - M_2)\left(k - \frac{1}{2}\right)}{\left[\left(\frac{a}{L} \right)^2 + \left(k - \frac{1}{2} \right)^2 \right]^{1/2}} + \right. \\ \left. M_1(1 - 0.1K) + M_2(0.95 + 0.1k) \right\}$$

$$H\left(\frac{3L}{4}\right) \approx \pi \left\{ \frac{(M_1 - M_2)\left(k - \frac{3}{4}\right)}{\left[\left(\frac{a}{L} \right)^2 + \left(k - \frac{3}{4} \right)^2 \right]^{1/2}} + M_1 + 0.77M_2 \right\}$$

$$H(L) \approx 2\pi \left\{ \frac{(M_1 - M_2)(k - 1)}{\left[\left(\frac{a}{L} \right)^2 + (k - 1)^2 \right]^{1/2}} + \right. \\ \left. M_1\left(1 - k\frac{L}{a}\right) + M_2(k - 1)^{L/a} \right\}$$

If $H(0) \approx H(L/2) = H(3L/4)$, it is possible to obtain from the above equations the values $k = 3/4$ and $M_2 = 1.3M_1$. Substitution of these values in the Equations 14 or in Equation 11 yields the following values for the magnetic field distribution at certain points along the axis of cylinder 13 and as substantially indicated by curve 19 of Fig. 4.

$$(15) \quad H(0) \approx 4\pi M_1$$

$$H\left(\frac{L}{2}\right) = 3.9\pi M_1$$

$$H\left(\frac{3L}{4}\right) \approx 4\pi M_1$$

$$H(0.9L) = 4\pi M_1(0.59)$$

$$H(L) = (4\pi M_1)(-4)$$

Thus, it has been found from the above equations that for $k = 3/4$ and $M_1/M_2 = 0.77$ there will be a very nearly uniform field distribution over three-quarters of the length of cylinder 13 as illustrated by curve 20 of Fig. 4. Therefore, the curve 20 represents the function

$$(16) \quad M_{(s)} = M_1 x \quad \text{for } x = -L \text{ to } L$$

while the curve 19 represents the summation of the functions

$$(17) \quad M_{(s)} = M_1 x \quad \text{for } x = -3/4L \text{ to } +3/4L$$

$$M_{(s)} = 3/4L(M_1 - M_2) + M_1 x \quad \text{for } x = 3/4L \text{ to } L$$

$$M_{(s)} = 3/4L(M_2 - M_1) + M_2 x \quad \text{for } x = -L \text{ to } -3/4L$$

where $M_2 = 1.3M_1$.

To obtain the magnetic field distribution as defined by Equation 11, it is necessary to establish a radial magnetization $M(x)$ on cylinder shell 13 as represented by curve 16 of Fig. 3. Referring to Fig. 5, apparatus is illustrated which is employed in a method for realization of a radial magnetization $M(x)$ to substantially satisfy Equation 11. The apparatus comprises a cylinder 21 having an inwardly extending flange 21a thereon substantially as shown to provide a substantially equal distribution of flux, a circular disc 22 closing one end of cylinder 21, and a solid cylindrical rod 23 axial with respect to cylinder 21 and movable longitudinally therein, said cylinder 21, disc 22, and rod 23 being composed of magnetic material such as soft iron. Associated with rod 23 and concentric thereto is a winding 24 having connected thereto a D.-C. current source 25 through a switch 26 which provides a reversing feature whereby the current through winding 24 may be reversed as desired.

The action of D.-C. current flowing through winding 24 is to establish a magnetic flux in rod 23 such that when shell 28 to be radially magnetized is inserted in the apparatus concentric to rod 23, the flux lines 27 will pass through shell 28 substantially at right angles to the walls of said shell. Thus, a path of magnetic material is provided for flux lines 27 through rod 23, shell 28 to be magnetized, cylinder 21, and disc 22 all of which provide together a means of radially magnetizing the shell 28, in sectional steps, as the shell is pulled out of the apparatus in steps about equal to length "b" shown on Fig. 5 after completion of each magnetization cycle. The length "b" is preferably approximately equal to the square of the inner diameter of permanent magnet 28 divided by four times the average diameter of permanent magnet 28.

A method employed to provide a radially magnetized cylindrical permanent magnet to satisfy the analytical discussion herein expounded may be performed by the apparatus of Fig. 5 in the following manner. The magnet 5 of Fig. 1 preferably consists of a cylindrical shell 13, Fig. 2, comprising two identical shells 28 and 29 whose inner diameters are sufficient to encircle tube 1. Each of the shells 28 and 29 are placed separately in the area between rod 23 and cylinder 21 to encircle rod 23 as indicated for shell 28 in Fig. 5. When placed in position the half shells may be magnetized separately to saturation as described above, but with reverse magnetic polarity. This reversed magnetic polarity is obtained by reversing the polarity of the magnetizing current from source 25 through means of reversing switch 26. After being magnetized separately to saturation these two half shells are then placed within the apparatus of Fig. 5 whereby a stabilizing operation of partial demagnetization takes place to obtain the magnetic distribution necessary to satisfy the law of magnetization $M(x)$ for a particular application of this electron-optical system. This stabilizing operation is accomplished by demagnetizing the half shells 28 and 29 in steps along the lengths as prescribed by the Equations 10 by the action of properly controlling the demagnetizing currents in winding 24 for action on various portions of said shells, as the shells 28 and 29 are withdrawn a length "b" therefrom in predetermined steps to the left from disc 22, Fig. 5. It may be further required to withdraw rod 23 in a manner to aid the stepped withdrawal of the shells to obtain the desired law of magnetization.

It is recognized that the methods herein disclosed to radially magnetize a cylinder in achievement of a desired

law of magnetization is not cut and dry, there is definitely a trial and error situation present. However, proper manipulation of the demagnetizing current in conjunction with the stepped withdrawal of the rod 23, changing the length of the flux path through air and thereby the strength of said flux, will enable the realization of the law of magnetization $M(x)$, as set forth by the conditions shown in Equation 10, to satisfy Equation 11. In the operation of demagnetization there is a tendency for the portion of the cylinders already demagnetized in a previous step to be further demagnetized or the magnetic distribution otherwise altered by the demagnetization step for the succeeding portion of said cylinders. However, experience in performing this process will enable an operator to make allowances for this interaction between demagnetization steps and can thereby control the demagnetizing current to compensate for this interaction and produce a cylindrical magnet magnetized radially to provide a substantially uniform axial magnetic field in accordance to the principles of this invention.

As an alternative method to magnetize the cylinders, as outlined above, two shells 30 and 31 having a length equal to one-half of the required magnet length may be fabricated from a plurality of individually magnetized radial segments, each segment being similar to segment 32. The segments forming shells 30 and 31 are radially magnetized by judicial winding of a magnetizing coil such that the segments of shell 30 has a magnetic polarity reversed with respect to the magnetic polarity of the segments of shell 31 as illustrated in Fig. 6. The segments of each ring are magnetized equally while those of adjacent rings are magnetized different amounts according to the law of magnetization hereinbefore described.

While I have described above the principles of my invention in connection with specific apparatus, it is to be clearly understood that this description is made only by way of example and not as a limitation to the scope of my invention as set forth in the objects thereof and in the accompanying claims.

I claim:

1. A permanent magnet comprising a continuous, constant diameter, uniform wall hollow cylinder of magnetic material magnetized radially the entire length thereof, said radial magnetization having an opposite polarity on opposite sides of the center portion of said cylinder and a gradient of magnetization from the ends of said cylinder toward said center portion whereby a substantially uniform magnetic field is produced axially of said cylinder for the major portion thereof.

2. A permanent magnet according to claim 1, wherein the radial magnetization is confined to individual segments arranged radially with respect to the axis of said cylinder with one polarity of each of said segments on the inner surface of said cylinder and the opposite polarity at the outer surface of said cylinder.

3. A permanent magnet comprising a continuous, constant diameter, uniform wall hollow cylinder of magnetic material magnetized radially the entire length thereof, said radial magnetization having an opposite polarity on opposite sides of the center portion of said cylinder and a gradient of magnetization from the ends of said cylinder toward said center portion for production of a substantially uniform axial magnetic field in accordance to the principles of this invention.

5 der toward said center portion for production of a substantially uniform magnetic field axially of said cylinder as expressed by the relationship

$$H(x_0) = 6\pi a^2 \int_{-L}^L \frac{M(x)(x-x_0) dx}{[a^2 + (x-x_0)^2]^{5/2}}$$

10 where a =radius of said cylinder, $M(x)$ =law of radial magnetization, x_0 =distance along the longitudinal axis of said cylinder defining an arbitrary point therealong with reference to the central transverse axis thereof, and x =longitudinal distance from the said central axis to a ring element dx of said cylinder.

15 4. In a traveling wave electron discharge device having means for producing a beam of electrons for flow along a given path, a radio frequency propagating structure disposed adjacent said path, and means to apply radio frequency waves for flow along said structure for interaction with electrons of said beam; a permanent magnet comprising a continuous, constant diameter, uniform wall 20 cylindrical shell of magnetic material disposed concentric of said path, said shell being radially magnetized for the entire length thereof, said radial magnetization having opposite polarity on opposite sides of the center portion of said shell and a gradient of magnetization from the 25 ends of said shell toward said center portion to provide a magnetic field of substantially uniform strength axially of and substantially coextensive with said path.

5 A device according to claim 4, wherein the gradient of radial magnetization on said shell produces a substantially uniform magnetic field as expressed by the relationship

$$H(x_0) = 6\pi a^2 \int_{-L}^L \frac{M(x)(x-x_0) dx}{[a^2 + (x-x_0)^2]^{5/2}}$$

35 where a =radius of said cylindrical shell, $M(x)$ =law of radial magnetization, x_0 =distance along the longitudinal axis of said shell defining an arbitrary point therealong with reference to the central transverse axis thereof, and x =longitudinal distance from said central axis to a ring 40 element dx of said shell.
